UNITED STATES PATENT OFFICE.

WILLIAM KOLLER, OF WHITE PLAINS, NEW YORK.

EMBROIDERY FRAME.

Application filed June 8, 1921. Serial No. 476,613.

To all whom it may concern:

Be it known that I, WILLIAM KOLLER, a citizen of the United States, residing at White Plains, in the county of Westchester 5 and State of New York, have invented certain new and useful Improvements in Embroidery Frames, of which the following is a full, clear, and exact specification.

This invention relates to embroidery frames especially designed for use on embroidery machines. This application is a continuation in part of an application filed by me on July 23, 1920, Serial No. 398,337, patented Dec. 13, 1921, No. 1,400,293.

It is the aim of the present invention to provide an embroidery frame of improved construction for holding the fabric to be embroidered in proper position during the embroidering thereof by a machine. The frame 20 is also especially adapted for use on a design positioning device, such as is disclosed in my above mentioned application, so that the design to be embroidered on the fabrics held by a plurality of frames may be uniformly 25 arranged thereon.

Another object is to provide a frame consisting of fabric clamping members which are adapted to firmly hold the most delicate fabrics between them without injuring the 30 same. A further object is to provide means for quickly clamping the members of the frame together and releasing them when desired, means being also provided for automatically separating said members, as soon 35 as they are released, in order to permit ready access to the fabric for adjusting or removing the same. Still another object is to provide the frame with means for supporting a roll of fabric while the end portion there- 40 of is clamped in the frame. The invention will be further hereinafter described in connection with the accompanying drawings, which constitute part of this specification, and then more specifically defined in the 45 claims at the end of the description.

In the accompanying drawings, wherein similar reference characters are used to designate corresponding parts throughout the several views:

Figure 1 is a side view of an embroidery frame constructed substantially in accordance with this invention, the clamping members thereof being shown in separated position.

Figure 2 is a side view of the free ends of the frame members locked together.

Figure 3 is a similar view of the hinged end portions of the frame members showing a roll of fabric supported thereby.

Figure 4 is a plan view of the lower 60 clamping member of the frame.

Figure 5 is an under plan view of the upper clamping member of said frame.

Figure 6 is a front end view of the lower clamping member, and

Figure 7 is a detailed sectional view through engaging portions of the clamping members of the frame drawn to a larger scale and showing the cushioning means for the fabric.

The frame comprises complementary clamping members or jaws 1 and 2 which are hinged at one end by pivot pins 3, Figs. 1 and 3. The member 1 is formed with a rectangular channel in its upper face consisting 75 of longitudinal channels 5 and communicating transverse channels 6, while the member 2 has a correspondingly arranged rectangular rib projecting from its lower face and consisting of longitudinal ribs 13 connected to transverse ribs 14. Said rectangular rib on the member 2 registers with the rectangular groove in the member 1 so that when said member 2 is swung downward into engagement with said member 1, said 80 rib will be inserted into said groove, as shown in Figures 2 and 7. Longitudinal grooves 5 and corresponding ribs 13 are preferably extended some distance beyond the transverse grooves 6 and ribs 14, as best 85 shown in Figures 4 and 5, in order to more firmly grip the fabric 30 without danger of tearing or otherwise injuring the same. Said fabric is preferably cushioned between a suitable lining 27 in the rectangular groove 95 of the member 1 and a similar covering 28 on the rectangular rib of the member 2, as shown in Figure 7.

In order to save metal, the members of the frame are made in skeleton form, as 100 shown, with a cross bar 8 at the free end of the member 1 and a corresponding cross bar 16 at the free end of the member 2. A pair of spaced lugs 19 extend from the central portion of the cross bar 16 longitudinally of the frame member 2, and between said lugs a locking lever 4 is pivoted at 26, said lever having a hook-shaped end 23 to engage below the cross bar 8 of the frame member 1 when the member 2 is engaged therewith. 105 The hook-shaped end 23 of the locking lever 4 is preferably covered with cushioning ma- 110

terial 24, as shown in Figure 2, to further protect the goods and to eliminate the noise of contacting metal parts. Said lever 4 is yieldingly pressed into locked position by a spring 260 supported between lugs 21 on the upper face of the cross bar 16 and having its inner extremities anchored in a slot 18 in said cross bar. The free end portion 25 of said spring 260 is preferably bent at an obtuse angle with the main portion of said spring, as shown in Figure 2, in order to more effectively bear upon the lever 4.

The pivoted end portion of the frame member 2 is formed with arched portions 17 reinforced by ribs 20 on their outer faces, to permit a roll of fabric 30 to be carried between said member 2 and the member 1 of the frame when said members are in engagement with one another, as illustrated in Figure 3. This arrangement permits the end portion of a roll of fabric to be clamped between the ribs and grooves of the members of the frame without being severed from the roll, and provides convenient means for supporting said roll so that it may be carried along with the frame during the design positioning and embroidering operations.

To automatically separate the members of the frame when they are released, a spring 22 is mounted around the pivot pins 3 connecting said members, as best shown in Figure 1, said pins 3 connecting the end portions 15 of the arches 17 of the member 2 with pairs of lugs 12 arranged in line with the side walls of the grooves 5 of the member 1. A cross bar 7 preferably extends between the spaced end portions of said member 1 bearing the lugs 12, and said cross bar may have a perforation 9 therein for engagement with a bolt or other holding means (not shown) for fastening the frame rigidly in place during the embroidering operation.

The free end of said member 1 is preferably provided with downwardly extending lugs 10 having notches 11 therein for engaging a rail or guide (not shown) of a design positioning device or embroidering machine. The cross bar 8 at the free end of the frame member 1 may also be perforated at 9 to receive suitable holding means for fastening the frame rigidly in position while the fabric clamped therein is being embroidered.

I claim:

1. An embroidery frame comprising interengaging clamping members having extensions hinged together at a distance from the clamping portions, one of said extensions being offset from the other providing storage space for a roll of fabric between said extensions while a portion of said fabric is clamped in the frame.

2. An embroidery frame comprising interengaging clamping members, one member having a groove and the other member having a rib to fit said groove, said members having extensions hinged together at a distance from their grooved and ribbed portions, and one of said extensions being offset from the other to provide storage space for a roll of fabric between said extensions while a portion of said fabric is clamped between the groove and rib of said members.

3. An embroidery frame comprising interengaging clamping members hinged together at one end, and a locking lever on the free end of one member for releasably engaging the other member, said lever having a hook-shaped end covered with cushioning material for the purpose specified.

In testimony whereof I have signed my name to this specification.

WILLIAM KOLLER.
